UNITED STATES PATENT OFFICE.

EMIL R. DRAVER, OF RICHMOND, INDIANA.

WINDOW-SASH HOLDER.

Application filed January 6, 1927. Serial No. 159,307.

My invention provides an improved sash holder for supporting sliding sash in various different adjustments, and, generally stated, the invention consists of the novel 5 devices and combinations of devices herein-after described and defined in the claims.

In the accompanying drawings, which illustrate the invention, like characters indicate like parts throughout the several views.

10 Referring to the drawings:

Fig. 1 is a fragmentary view in elevation, looking at the inside of a window frame and sash, the latter being held by friction supports designed in accordance with what is 15 believed to be the preferred form of the invention;

Fig. 2 is a section on the line 2—2 of Fig. 1; Fig. 3 is a fragmentary view partly in elevation and partly in vertical section showing 20 in detail the structure of the frictional holder illustrated in Figs. 1 and 2;

Fig. 4 is a horizontal section on the line 4—4 of Fig. 3;

Fig. 5 is a perspective showing the elements of the holder in Figs. 1, 2, 3 and 4 25 segregated or drawn apart, some parts being broken away;

Fig. 6 is a view corresponding to Fig. 3 but illustrating a slightly modified construction of the sash holder;

Fig. 7 is an edge elevation looking from the left toward the right of the sash and holder illustrated in Fig. 6, with the window frame removed;

30 Fig. 8 is another view corresponding to Fig. 3 but illustrating a still further modified construction; and

Fig. 9 is a section taken on the line 9—9 of Fig. 8, the window frame being removed.

40 Describing first the structure illustrated in Figs. 1 to 5, inclusive, the numeral 10 indicates a window frame of the usual construction except that weight boxes are not provided, the same frame being, as shown in

45 Fig. 2, set into a wall 11. The frame 10 has the customary inner and outer sash-guiding channels 12 and 13, respectively, in which work slidably lower and upper sashes 14 and 15, respectively. The guide channel 12,

50 as shown, is formed between an intermediate stop strip 16 and an inside stop strip 17, and the guide channel 13 is formed between said intermediate strip 16 and an outside guide

strip 18. The strips 16 and 17, as is usual, are preferably removable. 55

The friction device for supporting the two sashes are alike and hence the description of one will answer for the description of the other.

The main supporting element of the friction device is a smooth rod 19 provided at its upper end with a head 20 which, by a screw 21 or the like, is pivotally anchored to the window frame within the corresponding sash-guiding channel. This rod 19 works 60 freely through perforations in the arms of a yoke-shaped friction head 22 that is set into a mortise 23 formed in the adjacent edge of the sash, as best shown in Fig. 3. The mortise 23 holds the friction head 22 for 65 travelling movements with the sash but permits it to move sufficiently to adjust itself to the rod 19.

Working within the opening of the friction head 22 and between the upper and lower 70 arms thereof is a wedge-shaped friction block 24, the outer edge of which is grooved to fit the rod 19 and the inner edge of which is oblique and is seated against the abutment 75 carried by the friction head. This abutment 80 as shown in the preferred form is supported by the curved free end of a flexible strip of metal 25 which, at its other end, is anchored to the friction head by a rivet 26 or the like. The free end of this flexible abutment is engaged by an adjusting screw 27 that works 85 through the back of the friction head 22 and is adapted to be reached for adjustment by a screw driver inserted through a hole 28 formed in the sash. As shown, the screw 27 90 is held against accidental movements by a split spring washer 27a. A coiled spring 29, placed around the rod 19 and compressed between the lower arm of the head 22 and the lower end of the wedge-shaped friction block 24, 95 yieldingly presses the latter upward so that it will be lightly wedged against the rod 19 and the abutment 25 and will instantly grip the rod 19 when the sash 15 has been raised to any desired height. The adjustment of the screw 27 will usually be such that, when the sash is being raised or when the weight of the sash is relieved from the friction device, the friction block will not quite contact with the upper arm of the friction head 22, but 100 when the weight of the sash is allowed to

fall upon the friction device, the friction block 24, due to the light wedging action caused by the spring 29, will not, without additional downward pressure, follow the 5 friction head on its downward movement but will increase its wedging action between the abutment 25 and the rod 19 until it contacts with the upper arm of the friction head 22. The farther inward the adjustment screw 27 10 is turned, the greater will be the normal distance between the friction block 24 and the upper arm of the friction head 22, due to the outward taper of the friction block and, hence, the greater will be the wedging action 15 before said friction block 24 and the upper arm of said friction head come into contact on their downward movement and limit said wedging action.

Obviously, this friction device will offer 20 any desired resistance to downward movements of the sash, but it will offer only a very slight resistance to upward movement of the sash; and this, of course, is desirable because the weight of the sash always exerts downward force. The adjustment of the friction device can be made such that it will afford the proper support for preventing accidental dropping of the sash but will, nevertheless, permit the sash to be raised or lowered by the 25 application of a very small amount of manually applied force.

Obviously, in the frictionally engaged connections described, there is sufficient flexibility to permit the sash supported thereby at 25 one side only to sag at its unsupported side and thereby normally pinching and frictionally engaging the window frame with sufficient force to prevent rattling of the sash under the action of the wind. The objection 40 to the rattling of the sash is too well known to require any extended discussion and it is, therefore, sufficient to further state that by this simple expedient a very objectionable feature found in sash supported at both sides 45 is removed without cost or, rather, under a reduced cost.

Inasmuch as the rods 19 are pivotally supported from the upper ends, it is an easy matter, simply by the removal of the stop strips, 50 to swing the sash inward to a position in which the sash may be slid off from or slid onto the supporting rod 19 while the latter is in an oblique position. This is not only a great advantage in the initial application 55 of the sash but in the removal for repairs, cleaning or painting.

The construction illustrated in Figs. 6 and 7 is like that illustrated in Figs. 1 to 5, inclusive, except that the friction head 22 at 60 its lower end is provided with an enlarged rounded anchoring lug 30 that is seated in a closely fitting seat formed in the sash, thereby anchoring the friction block to the sash without requiring contact between the upper 65 and lower ends of the head and its seat 23.

In the modified construction illustrated in Figs. 8 and 9, the yoke-shaped friction head 22^a, in lieu of the adjustable abutment shown in Figs. 1 to 5, inclusive, has a fixed abutment in the form of a lug 31 that engages the 70 oblique face of the wedge-shaped friction block 24^a; the lug 30^a, at the lower end of the block 22^a is anchored to the sash by a screw 32; and the upper end of the wedge-shaped friction block 24^a is seated against a screw 33 75 when said sash is held suspended by the friction device, said screw having screw-threaded engagement through the upper arm of the head 22^a. The action of this modified form is practically the same as that shown in the other figures except that the wedging action of the friction block is limited by its contact with the screw 33 instead of the upper arm of the head 22.

Figures 6 to 9, inclusive, illustrate two of 80 the many modifications that may be made within the scope of the invention disclosed and claimed. In actual practice, the efficiency of the friction device herein disclosed and claimed has been demonstrated.

What I claim is:

1. A window holding device comprising a friction rod having means for suspending the same from a window frame, a friction head arranged to be applied to a window sash and having an abutment thereon, said rod being frictionally movable through said head, and a wedge-shaped friction block interposed between and frictionally engageable with said rod and the abutment on said head. 100

2. A window holding device comprising a friction rod having means for suspending the same from a window frame, a friction head arranged to be applied to a window sash and having an abutment thereon, said rod being frictionally movable through said head, a wedge-shaped friction block interposed between and frictionally engageable with said rod and the abutment on said head, and means 105 for adjusting said abutment.

3. A window holding device comprising a friction rod having means for suspending the same from a window frame, a friction head arranged to be applied to a window sash and having an abutment thereon, said rod being frictionally movable through said head, a wedge-shaped friction block interposed between and frictionally engageable with said rod and the abutment on said head, and a spring reacting against said head and block 115 and compressing the latter into frictional engagement with said abutment and rod.

4. A window holding device comprising a friction rod having means for suspending the same from a window frame, a yoke-like friction head adapted to be seated in a window sash for movements therewith, said head having an abutment opposed to said rod and said rod working through the spaced arms of said head, a friction block held in the longitudinal 125 130

groove engaging said rod and having an oblique face engaging said abutment, and a spring pressed between said head and block and compressing said friction block into engagement with said rod and abutment.

5. The combination with a window frame and a sash slidably mounted therein, a friction rod pivotally suspended from said frame, a yoke-like friction head seated in one edge

of said sash, said rod working with frictional engagement through the upper and lower arms of said head, an abutment on said head, a wedge-shaped friction block frictionally engageable with said rod and abutment, and means for varying the frictional engagement of said block with said rod and abutment.

In testimony whereof I affix my signature.

EMIL R. DRAVER.
